UNITED STATES PATENT OFFICE.

ROGER WILLIAM WALLACE AND EUGENE WASSMER, OF LONDON, ENGLAND.

PROCESS FOR THE PRODUCTION OF AMMONIA.

1,083,232.

Specification of Letters Patent.

Patented Dec. 30, 1913.

No Drawing.

Application filed August 18, 1912. Serial No. 785,325.

To all whom it may concern:

Be it known that we, ROGER WILLIAM WALLACE, residing at 2 Harcourt Buildings, Temple, London, E. C., England, and EUGENE WASSMER, of 42 Manor House, Maryle-

bone Road, London, N. W., England, have invented a new or Improved Process for the Production of Ammonia, of which the following is a specification.

10 Our invention is for a novel process for obtaining ammonia from nitrogen.

In carrying out our invention we pass nitrogen over any metals (at the required temperature) capable of forming a nitrid which nitrid is capable of being subsequently transformed into a sulfid. This nitrid we divide into two portions. Over one portion (hereinafter termed the first portion) we pass sulfureted hydrogen so as to release the 20 nitrogen as sulfid of ammonium and so as to form a sulfid of the metal. The other portion of the nitrid (hereinafter termed the second portion) is used to obtain a chlorid of the metal and this may be done for example in one of the two following ways:—

(a) The nitrid is treated with steam or moist air and in some cases an alkali in solution so as to free the ammonia, the oxid or hydrate formed being treated with hydrochloric acid so as to obtain the chlorid, or (b) The nitrid is treated with hydrochloric acid gas so as to form ammonium chlorid and a chlorid of the metal. The sulfid and chlorid of the metal thus obtained are mixed together and introduced into an electrolytic bath and treated so that the metal is formed throughout the bath. Or the metal may be drawn off in the liquid state. This metal is then treated to form nitrid as hereinbefore mentioned. The chlorids of sulfur and/or the products of their dissociation which are given off from the bath are used to obtain sulfureted hydrogen and hydrochloric acid gas in any well known way which gases are

45 used to obtain sulfid and chlorid from the nitrid obtained in the process as hereinbefore mentioned. The sulfid and chlorid thus obtained are then treated in the electrolytic bath and the cycle of operations is repeated.

50 In the case of magnesium we find that good results are obtained by dividing the nitrid in the proportions of three quarters and one quarter, the larger portion to be converted into sulfid and the lesser portion into chlorid. This is for replenishing the bath when working. When starting the

process however it is desirable in order to secure good conditions in the bath to put in a larger proportion of chlorid, say equal portions of sulfid and chlorid.

60

When we have a convenient extraneous source of chlorid it is unnecessary to transform the whole of the metal obtained into nitrid. It is only necessary to transform into nitrid such portion of the metal as will give a quantity of nitrid corresponding with the portion which we have hereinbefore termed the first portion and which is used to obtain the sulfid.

65

Sulfureted hydrogen is partly recovered 70 from the sulfid of ammonium when treated with acid as in the case of the manufacture of sulfate of ammonia and partly from the sulfur chlorid which we prefer to decompose in water sulfur being deposited and hydrochloric acid formed. The deposited sulfur may be transformed into sulfureted hydrogen by any well known process.

75

In the case of magnesium for example the treatment of the nitrid with hydrochloric acid 80 gas is carried out at ordinary temperature. Should the reaction cause a rise in temperature suitable means for cooling and maintaining at ordinary temperature may be employed if judged necessary.

85

Having thus described our invention what we claim as new and desire to secure by Letters Patent is:—

1. The herein described cyclic process of producing ammonia from free nitrogen, 90 which comprises treating a metal with nitrogen to form nitrid, separating said nitrid into two portions, converting one portion of the nitrid into a metal sulfid and converting another portion of the nitrid into a metal 95 chlorid, electrolyzing the mixture of said metal chlorid and sulfid to produce a metal and sulfur chlorid and repeating the cycle of operations.

2. A cyclic process for the production of 100 ammonia which comprises (1) treating a metal with nitrogen to form nitrid, (2), dividing the nitrid into two portions, (3) treating one portion with hydrogen sulfid to form metal sulfid and ammonium sulfid, 105 and treating the other portion with hydrochloric acid to form metal chlorid and ammonium chlorid (4) electrolytically converting said metal sulfid and metal chlorid into metal and sulfur chlorid; reintroducing the 110 metal into the first step of the process, and (5) converting the sulfur chlorid into hy-

drogen sulfid and hydrochloric acid, for use in the third step of the process.

3. A cyclic process for the production of ammonia, which comprises (1) treating metallic magnesium with nitrogen to form magnesium nitrid, (2) dividing said nitrid into two portions, (3) treating one portion with hydrogen sulfid to form magnesium sulfid and ammonium sulfid, and treating the other portion with hydrochloric acid to form magnesium chlorid and ammonium chlorid, (4) electrolytically converting said magnesium sulfid and magnesium chlorid into metallic magnesium and sulfur chlorid; reintroducing the metallic magnesium into the first step of the process, and (5) converting the sulfur chlorid into hydrogen sulfid, and hy-

drochloric acid for use in the third step of the process.

4. In a cyclic process for the production of ammonia substantially as set forth the steps of dividing the nitrid formed into two portions and treating one portion to form a sulfid and the other portion to form a chlorid. 25

In witness whereof we have signed our names to this specification in the presence of two subscribing witnesses.

ROGER WILLIAM WALLACE.
EUGENE WASSMER.
